UNITED STATES PATENT OFFICE.

WALTER V. REID, OF RICHMOND, INDIANA, ASSIGNOR TO PETTIS A. REID, OF RICHMOND, INDIANA.

FEEDING MECHANISM FOR WIRE-FENCE MACHINES.

1,242,595.

Specification of Letters Patent.

Patented Oct. 9, 1917.

Application filed March 24, 1917. Serial No. 157,094.

To all whom it may concern:

Be it known that I, WALTER V. REID, a citizen of the United States, residing at Richmond, in the county of Wayne and

5 State of Indiana, have invented certain new and useful Improvements in Feeding Mechanisms for Wire-Fence Machines; and I do hereby declare the following to be a full, clear, and exact description of the invention, 10 such as will enable others skilled in the art to which it appertains to make and use the same.

This invention relates to mechanism for feeding wire and other flexible material longitudinally, and more particularly to wire fabric weaving machines used for making wire fences, wherein the stay wire is fed longitudinally or endwise across a series of strand wires into position for the action of 20 a series of loop-forming and twisting devices and associated mechanisms, whereby loops are formed in the stay wire and wrapped around the strand wires at predetermined distances apart as the strand wires are drawn intermittently through the machine.

The object of my invention is to provide a novel and efficient feed mechanism of the character referred to whereby the wire from 30 which the stays are to be formed, or other flexible material, may be fed to the wire working machine automatically from the coil of wire longitudinally or endwise in desired lengths to form alternately long and 35 short stay lengths. A further object is to provide a feed mechanism of the character referred to composed of few parts compactly arranged and adapted to be easily removed and replaced or repaired when 40 worn or broken, and which at the same time shall be simple in construction, inexpensive in manufacture and reliable and durable in practical use.

The invention will first be hereinafter 45 more particularly described, with reference to the accompanying drawings, which are to be taken as a part of this specification, and then pointed out in the claims at the end of the description.

50 In said drawings, wherein I have illustrated two different forms of feed mecha-

nism each adapted to feed one length during the operation of one cycle and a different length during the next cycle of movement,

55

Figure 1 is a front elevation of a feed mechanism embodying my invention;

Fig. 2 is a front elevation of another form or modification;

Fig. 3 is a detail perspective view of the 60 cam used for shifting the stay wire guiding means shown in Fig. 1 or the segmental feed roll shown in Fig. 2, so as to adapt the mechanism to feed wire or other flexible material longitudinally alternately in long 65 and short lengths; and

Fig. 4 is a perspective view of the feed roll composed of unequal segments.

Referring to said drawings, in which the same reference letters are used to denote 70 corresponding parts in different views, the letter A may denote the machine frame on which the feed mechanism is mounted. The letters B, C and D denote, respectively, a power shaft, the cam shaft and a counter-shaft journaled in said frame. When revolved at the same speed as the time shaft of the machine to which the material is being fed the power shaft may be an extension of said time shaft and journaled or not, as 80 may be necessary, in the frame of the feed mechanism. The counter-shaft D may be journaled in suitable bearings bolted or otherwise secured to the machine frame, as shown, parallel with the power shaft. The 85 feed roll drive shaft E extends above the machine frame in which it is journaled and carries a bevel pinion or gear wheel in mesh with a similar bevel pinion or gear wheel on the shaft D, which may be driven by 90 means of a chain F extending from a sprocket wheel on the power shaft B to a similar sprocket wheel on the counter-shaft, while the shaft C is driven by a drive chain G extending from a sprocket wheel on the 95 power shaft B around a larger sprocket wheel on the cam shaft C. Said sprocket wheels are so proportioned and the movement so timed as to impart the desired rotary movement to the feed rolls and the de- 100 sired reciprocating movement to the wire guiding means or the feed-roll shifting

means, for feeding alternately material in different lengths, as hereinafter described. H and H¹ denote a pair of feed rolls which are arranged in slightly separated relation and fixed to the shaft E so as to revolve therewith, being held apart by means of a spacing plate or flange h, on one roll fitting against or upon the other roll so as to provide what may be termed a neutral space between the two rolls for a purpose herein-after stated. Each of the rolls H, H¹ has a peripheral portion thereof cut away, as shown in Fig. 4, to form unequal segments or contact surfaces of different lengths to adapt one segment and the co-acting feed roll to feed a greater length than the other segment. The feed rolls I, I¹ are also arranged in slightly separated relation adjacent the segments H and H¹ and have therebetween a neutral space i arranged in the plane of the neutral space h between the rolls H, H¹, the peripheries of the co-acting feed rolls being normally separated sufficiently for the passage therebetween of the wire or other material that is being fed longitudinally through the machine by means of said rolls. On the shaft C is fixed a cam K on which the lower end of a reciprocating bar L or a friction roller on the lower end of said bar may rest, to be operated thereby. Said bar L carries at its upper end a small feed wire guide or tube M which receives and guides the stay wire longitudinally through the machine, between one or the other of the segments and the co-acting feed roll. The bar L may be supported and guided in its reciprocatory movements in eyes or sockets n, n¹ on the projecting ends of brackets N and N¹, which may be bolted or otherwise secured to the machine frame, as shown. A coiled or other suitable spring O, placed on the bar L between the bracket N and a collar o on said bar L, tends to force said bar downwardly and hold the friction device or roller on the lower end thereof in engagement with the actuating cam K. The collar o may be secured on the bar L by means of a set screw to adapt it to be adjusted for varying the pressure of the spring. The rollers I, I¹, or equivalent rolling means, may be mounted on a stub shaft which has its bearings in a socket formed integrally with or secured to a lever P, which is pivotally mounted on the machine frame, conveniently by means of ears or lugs on the tubular part of the lever P, apertured to receive a pivot bolt or pin p engaging registering apertures in similar lugs projecting from the machine frame. The tube or socket on the lever P may be formed integrally with a depending portion or extension of the longer arm P¹ of the lever P, and to said longer arm is connected at its lower end one end of a coiled or other suitable spring Q, the other end

of which may be adjustably secured to the machine frame by means of an eye-bolt q passing through a hole in a bracket on the machine frame and having a nut screwed thereon for adjusting the tension of the spring which serves to hold the lever P in contact with an adjusting screw x carried by a bracket X projecting from the machine frame, as shown, whereby the working faces or peripheries of the feed rolls are prevented from coming into contact and are kept at the desired distance apart to permit the passage of the feed wire between the peripheral surfaces of the adjacent feed rolls and adapt the latter to grip and hold the wire therebetween with sufficient pressure to feed the required length as the rolls revolve. The cam K is constructed with a peripheral projection k which engages the lower end of the movable bar L, or the friction roller thereon, and raises said bar sufficiently to bring the stay wire centrally between the peripheries of the uppermost feed rolls, that is, between the roll I and the segment H, and hold the wire through the wire guiding means carried by the bar L in such position until a sufficient number of revolutions of the feed rolls has been made to feed the desired length, whereupon the spring O will force the bar L downwardly so as to bring its lower end into engagement with the arc-shaped portion or cam surface k¹ of the cam K at one side of the boss k and at the same time bring the wire guiding means M and feed wire into the plane of the neutral spaces between the adjacent pairs of feed rolls where the wire is held until the loop-forming and wrapping devices have attached the previously fed stay to the strand wires, and thereupon, the strand wires being drawn through the machine the length of a stay space, the bar L will be further depressed by the spring O, bringing its lower end or the roller thereon into engagement with the recessed portion k² of the cam K, which brings the wire guiding means M centrally of the two lowermost feed rolls, and the feed wire being clamped therebetween, as the rollers are caused to revolve, another and shorter stay length will be fed, and as the rotation of the cam is continued the bar L will be caused to engage the arc-shaped portion k³ of the cam K and thereby raise the rod L sufficiently to bring the wire guiding means M into alignment with the neutral space between the feed rolls, where it will be held for a sufficient period of time to permit the application of a previously fed stay or stay length, and thereupon the bar L will be again raised by the boss k on the cam K, so as to bring the feed wire and guiding means into operative relation to the uppermost feed rolls, and so on, so as to intermittently feed the material alternately in

long and short lengths, the length fed depending upon the length of the contact surface of the segment with which the adjacent co-acting feed roll is engaged. A gear wheel R on the shaft E in mesh with a pinion R¹ on the stub shaft which carries the feed rolls I, I¹, may be used for imparting simultaneous rotary movement to the two pairs of rolls when the shaft E is revolved.

5 In the form shown in Fig. 2 of the drawings, instead of the rolling means shown in Fig. 1, a single feed roll I² is employed, being arranged normally opposite the neutral space between the adjacent feed rolls H² and H³, and the pinion R² on the stub shaft which engages the gear R on the driving shaft E¹ is provided with teeth of sufficient length to permit a limited vertical or forward and back movement of the gear R.

10 without disengaging the driving gear and pinion, and the rolling means I² adjacent the segmental feed roll is supported and spring-pressed toward the segmental feed rolls in the same manner as described with

15 reference to the rolling means and associated parts shown in Fig. 1, but instead of the reciprocating bar L carrying the wire guiding means M, a reciprocatory or forward and back movement is imparted to

20 the segmental feed rolls by means of a pivotally mounted bell-crank lever S, the longer pendant arm s of which is connected at or near its lower end with a coiled or other suitable spring T, the other end of

25 which is preferably connected to an eye bolt adjustably secured to the machine frame in the same manner as the spring Q in Fig. 1, so that the tension of the spring may be varied to vary the pressure contact

30 on the feed wire. The short arm s¹ of the lever S is bifurcated or forked, and the forked ends thereof are provided with open-ended slots to receive studs or pintles u, projecting in opposite directions from a

35 divided yoke U, which is fitted in a groove provided therefor by means of spaced flanges on a sleeve E² which is slidably mounted upon the shaft E¹ and caused to revolve therewith by means of a spline and

40 groove connection or a key on the shaft engaging a groove on the interior of the sleeve and extending longitudinally thereof to permit the sleeve to slide on while revolving with the shaft; the feed rolls H² and H³

45 being secured to said sleeve and movable therewith, together with the spur wheel or gear R to the hub of which the feed rolls H² and H³ are rigidly secured. The long arm of the lever S carries a friction roller

50 s² (indicated in dotted lines) arranged to bear upon and be actuated by the cam K as the cam shaft revolves to raise and lower the segmental feed rolls in the same manner that the reciprocating bar L is raised and

55 lowered, so that by the rocking movements

of the lever S the segments H² and H³ will be brought alternately into alignment with the single roll I² for feeding alternately a long and a short stay length as described with reference to the operation of the mechanism shown in Fig. 1, the cam K being adapted to first bring one large roll or segment into alignment with the adjacent feed roll I², then into alignment with the neutral space centrally of the two segments, and then into alignment with the other large feed roll or segment, and again into the neutral space, and so on, so as to feed alternately long and short lengths of wire or other material, the length of feed being determined by the extent of peripheral contact between the segment and the co-acting feed roll.

70 Suitable guiding means for the material being fed can be mounted upon a bracket or fixed part of the machine frame to guide the material to the feed rolls and guiding means to receive the material that is being fed can also be mounted upon a bracket or other fixed part of the machine frame on the opposite side of the feed rolls, if desired. 75 When feeding a stay feed wire to a fence making machine it may be and usually is desirable to pass the wire through a wire straightener, such as shown in Patent No. 1,160,089, granted Reid, Reid and Kelley, 80 November 9, 1915, having two series of grooved rolls mounted in different planes so that the wire may be drawn between the two sets of rolls and straightened; and such wire straightener may be mounted on a shelf or bracket cast integrally with or secured to the machine frame in such manner that the straightener so mounted may serve as one guide for guiding the wire to the feed rolls. 85 A tubular guide such as shown in 90 said patent may also be mounted upon the fence machine and extended close up to the feed rolls to receive the wire as fed by the rolls.

100 It will be understood of course that the same result might be accomplished by imparting a reciprocatory movement to the single feed roll instead of the segments, and that the required movement may be imparted to the feed roll shafts and cam shaft 105 by other means than sprocket wheels and chains, as for instance, by bevel or spur gearing, and that if the machine with which this feeding mechanism is to be used has shafts properly timed, the frame design of 110 the feed mechanism can be changed to suit the positions of such shafts when extended, or the feed roll drive shaft E or E¹ can be directly connected to one of the machine shafts and motion imparted to the lever S 115 by a cam mounted on a shaft within the machine frame so as to dispense with the chains and sprocket wheels and bevel gearing of the specific form shown.

120 While my improved feed mechanism is 130

designed and adapted especially for use upon wire fence making machines, it is obviously adapted for use in feeding flexible material to other machines, for instance, for 5 feeding strip material to punch presses, or other machinery, in either unequal or equal lengths, and it will be understood that the invention is not restricted in its application to wire fence making machines.

10 It should be borne in mind that the shifting of the stay feed wire sidewise by the means shown in Fig. 1, or the shifting of the feed rolls sidewise by the means shown in Fig. 2, for the purpose of bringing the 15 stay feed wire into a neutral position between the feed rolls or into position to effect the infeed of the wire longitudinally, takes place while the cut away portion of the larger roll or segment is passing the 20 smaller roll, and the feed wire may be held in the neutral position between the feed rolls while the latter are making one or more revolutions, the period of time it is so held, depending upon the amount of idle 25 time wanted between successive feeds.

My invention also contemplates the use of a single pair of rolls for feeding the same lengths of wire successively or different lengths alternately. To feed the 30 same lengths successively, the rolls H and I or H¹ and I¹ are omitted and an actuating cam used similar to the cam K but without the recess k²; and in such case the length of the working face k would depend upon 35 the number of revolutions required to feed the required length of wire, while the length of the faces k¹ and k³ would depend upon the number of idle turns of the rolls required. I may feed alternately different 40 lengths of wire by means of a single pair of rolls providing the lengths to be fed are multiples of what the segment roll will feed during one revolution. For instance, if one length requires one turn and the other 45 length requires two, three or four turns, or if the first length requires two turns and the second length requires three or four turns, the working face k of the cam K should be made the length necessary to hold 50 the wire in the plane of the rolls during the required number of revolutions of the rolls for the first length while for the second length the cam would be provided with another raised portion like the part k instead of the recess k² and of sufficient length 55 to hold the wire in the plane of the rolls for the required number of turns.

Various other changes may be made in the details of construction and arrangement of parts without departing from the spirit and scope of my invention; hence I do not desire to be limited to the specific construction illustrated and described.

Having thus described my invention, what

I claim as new and desire to secure by Letters Patent of the United States is:

1. In a feed mechanism of the character described, means for feeding flexible material longitudinally alternately in long and short lengths, comprising a revoluble shaft 65 carrying a pair of feed rolls spaced apart, adjacent rolling means arranged to co-act with said pair of rolls to feed alternately a long and a short length, guiding means and means for changing the position of said guiding means relatively to said rolls whereby the material is brought alternately between the peripheries of one of said pair of rolls and said rolling means.

2. Mechanism for feeding wire or other 70 flexible material longitudinally alternately in long and short lengths, comprising a pair of feed rolls arranged in slightly separated relation, a smaller pair of rolls arranged in slightly separated relation with the periphery of each adjacent the periphery of one of the larger pair of rolls, means for 75 guiding the material between the peripheral portions of adjacent rolls, and means for shifting said guiding means so as to cause the material to be gripped and fed first by one and then by another of the larger rolls and a co-acting smaller roll.

3. In combination, a revoluble shaft 80 carrying a pair of feed rolls arranged in slightly separated relation, a stub shaft carrying another pair of feed rolls arranged in slightly separated relation with their peripheries adjacent the peripheries of the larger rolls, means for revolving the larger 85 and smaller pairs of rolls in opposite directions, means for yieldingly forcing the smaller feed rolls toward the larger rolls, means for guiding a wire longitudinally between the peripheries of the two pairs of rolls, and means for shifting said guiding 90 means so as to bring the material to be fed alternately between the peripheries of one of the larger and one of the smaller rolls and then between the peripheries of the 95 other two rolls.

4. In combination, a revoluble shaft 100 carrying a feed roll composed of unequal segments separated to provide an intervening 105 neutral space, adjacent feed rolls arranged in slightly separated relation beside said segments, means for guiding a wire longitudinally between the peripheries of the two pairs of rolls, means for revolving said 110 rolls, and means for shifting said guiding means so that the material will be fed first between the larger segment and one of the smaller rolls and then between the smaller segment and the other small roll, and means 115 for revolving said rolls.

5. In combination, a revoluble shaft carrying a feed roll composed of unequal segments separated to provide an intervening 120

neutral space, adjacent feed rolls arranged in slightly separated relation beside said segments, means for guiding a wire longitudinally between the peripheries of the two pairs of rolls, means for revolving said rolls, and means for shifting said guiding means so that the material will be fed first between the larger segment and one of the smaller rolls and then between the smaller segment and the other small roll, means for revolving said rolls, and pressure exerting means for holding the material between the peripheral portions of the active feed rolls.

6. In a wire fabric weaving machine, means for automatically feeding alternately a long and a short length of wire endwise, comprising a revoluble feed roll composed of unequal segments arranged in slightly separated relation so as to provide an intervening neutral space, a pair of revoluble feed rolls arranged in slightly separated relation adjacent the first mentioned pair of rolls with their peripheries slightly separated therefrom, means for revolving said rolls, pressure exerting means for forcing the peripheries of one pair of rolls toward the peripheries of the other pair, means for guiding a wire longitudinally between the peripheries of the two pairs of rolls, and means whereby said guiding means is brought alternately into position for the material to pass first between the peripheries of one of the segments and an adjacent feed roll and then between the peripheries of the other segment and adjacent feed roll, so as to feed material in different lengths.

7. In a wire fabric weaving machine, means for automatically feeding alternately a long and a short length of wire longitudinally or endwise, comprising a revoluble shaft carrying a pair of unequal segments arranged in slightly separated relation to provide an intervening neutral space, rolling means beside said segments adapted to coact alternately therewith so as to feed material alternately in different lengths, a driving shaft and means associated therewith for revolving said segments and rolling means, including a cam and a reciprocating device actuated by said cam for bringing the wire alternately into position for the action of one of the segments and an adjacent feed roll and then into position for the action of another segment and an adjacent feed roll.

8. In a wire fabric weaving machine, a revoluble shaft carrying a pair of feed rolls composed of unequal segments arranged in slightly separated relation so as to provide an intervening neutral space, a stub shaft carrying a pair of feed rolls arranged in slightly separated relation beside said segments so as to provide a neutral space in the plane of the neutral space between the seg-

mental rolls, a reciprocating bar carrying means for guiding a wire lengthwise between the peripheries of the segments and adjacent feed rolls, means for revolving the two pairs of rolls, and means for yieldingly forcing one pair of rolls toward the other pair, together with means for shifting said guiding means so as to cause one of the segments and an adjacent feed roll to feed a given length of wire and then another segment and another feed roll to feed a different length of wire.

9. Mechanism for feeding wire and other flexible material longitudinally alternately in comparatively long and short lengths, comprising a revoluble shaft carrying a pair of feed rolls composed of unequal segments arranged in slightly separated relation so as to provide an intervening neutral space, rolling means adjacent said segments, and means whereby said rolling means is caused to operate alternately with said segments so as to feed material alternately in different lengths.

10. Mechanism for feeding longitudinally wire and other flexible material alternately in different lengths, comprising a pair of revolvably mounted feed rolls composed of unequal segments arranged in slightly separated relation so as to provide an intervening neutral space co-extensive with said segments, rolling means revolvably mounted beside said segments, and means for bringing said segments alternately into position for cooperation with said rolling means for feeding material alternately in different lengths.

11. In combination, a revoluble shaft carrying a feed roll composed of unequal segments slightly separated, a pivotally supported lever carrying a pair of smaller feed rolls arranged beside said segments and also slightly separated, wire guiding means between the peripheries of said segments and smaller rolls, a slidably mounted bar carrying said guiding means, a cam operating on said bar to move said guiding means alternately into position to cause first one segment and then the other to coact with one of said smaller rolls in feeding the desired length, means for holding said bar in engagement with said cam, means acting on said lever for yieldingly forcing the smaller rolls carried thereby toward said segments, and a stop to limit such movement.

12. In combination, a pair of feed rolls and co-acting rolling means for feeding endwise a feed wire or other material; said pair of rolls being slightly separated to provide a neutral space, wire guiding means, and means for shifting the feed wire sidewise back and forth into said neutral space and between said rolling means and the periphery of one of said pair of rolls.

13. In a feeding device of the character described, a feed roll and co-acting rolling means whereby wire or other material placed therebetween may be fed lengthwise by the rotation of said feed roll and rolling means, a feed-wire guide and means for shifting the position of said guide relatively to said feed roll alternately into and out of

operative relation to said feed roll and co-acting rolling means.

In testimony whereof I affix my signature in the presence of two witnesses.

WALTER V. REID.
